UNITED STATES PATENT OFFICE.

SVERRE THUNE, OF MADSERUD, VESTRE AKER, NEAR CHRISTIANIA, NORWAY.

ROTARY PISTON-PUMP.

1,152,453.

Specification of Letters Patent

Patented Sept. 7, 1915.

Application filed March 30, 1914. Serial No. 828,186.

To all whom it may concern:

Be it known that I, SVERRE THUNE, a subject of the King of Norway, residing at Madserud, Vestre Aker, near Christiania, Norway, have invented certain new and useful Improvements in Rotary Piston-Pumps; and I do hereby declare the following to be a full, clear, and exact description of the invention, such as will enable others skilled in the art to which it appertains to make and use the same, reference being had to the accompanying drawings; and to letters or figures of reference marked thereon, which form a part of this specification.

This invention relates to piston pumps having cylinders diametrically disposed in a rotary shell wherein a relative reciprocating movement between the cylinders and pistons is obtained by rotating the shell on an axis displaced from the axis about which the pistons are rotated.

The object of the invention is to provide a pump of this kind wherein a series of diametrically disposed pistons and cylinders may be arranged along the axis of the rotary shell, especially with the idea of using the apparatus as a central plunger lubricator. This is attained by the construction disclosed herein, reference being had to the accompanying drawings in which,

Figure 1 represents a radial cross section of a rotary pump of this kind, taken on line 1—1 of Fig. 2; and Fig. 2 represents a central vertical section through the pump of Fig. 1.

In the embodiment shown in the drawings, the pistons *a* are inserted in and fastened to the shaft *d*, which is provided with a slotted crank-guide *f* at each of its ends, embracing a rotary guide head *e*. One of the guide heads carries a journal mounted in the end wall of the tank *g*, while the other guide head is a part of the driving shaft *h*. The shell *c* carries the diametrically disposed cylinders *t* and is fitted in the casing *b* which is integral with the surrounding oil tank *g*. The axis about which the shaft *d* is rotated is parallel to but displaced from the axis of rotation of the shell *c*. The shaft *h* drives the shaft *d* and the pistons *a* pull the shell *c* around in the casing *b*, reciprocating movements between the pistons *a* and the cylinders *t* being produced as a result of the displaced disposition of the axes of rotation. The arrangement provides for the necessary relative sliding movements of the

guide heads *e* in the slots of the crank-guides *f* during the rotation of the shaft *h*.

The casing *b* is provided with inlets *i* in line with the individual pairs of diametrically disposed pumps, and with corresponding outlets *h*. During rotation in the direction indicated in Fig. 1, the pistons suck oil or other medium from the tank *g* into the cylinders, while the cylinders register with the inlets *i*, and they discharge it under pressure while the cylinders register with the outlets *h*. As shown, the outlets *h* communicate with individual conduits adapted to be connected to pipes leading to different parts of the machine to be lubricated, for example.

Having thus described my invention, what I claim is:

1. In rotary piston pumps, a pump cylinder rotatable about a transverse axis, a piston rotatable about a transverse axis eccentric relatively to the axis of rotation of the cylinder and reciprocative therein during rotation, and driving means for rotating the cylinder and piston on said axes.

2. In rotary piston pumps, a pump cylinder rotatable about a transverse axis, a piston rotatable about a transverse axis eccentric relatively to the axis of rotation of the cylinder and reciprocative therein during rotation, and driving means for rotating the cylinder and piston on said axes and including a sliding connection compensating for the eccentricity of said axes.

3. In rotary piston pumps, a pump cylinder rotatable about a transverse axis, a piston rotatable about a transverse axis eccentric relatively to the axis of rotation of the pump cylinder and reciprocative therein during rotation, and driving means for rotating the cylinder and piston on said axes and including a crank-guide and a guide head slidable therealong transversely of the piston.

4. In rotary piston pumps, a rotatable shell carrying a plurality of radially disposed pump cylinders, a rotatable shaft carrying a plurality of pistons reciprocative in respective cylinders and having a crank-guide at each end, a guide head for each crank-guide slidable therealong transversely of the pistons and journaled for rotation on an axis eccentric to the axis of rotation of the shell, and driving means for rotating the shell and shaft.

5. In rotary piston pumps, a tank, a cylin-

der fastened to the tank, a shell rotatable in the cylinder and carrying a plurality of diametrically disposed pump cylinders, a rotatable shaft carrying a plurality of pistons 5 reciprocative in respective pump cylinders and having a crank-guide at each end, a guide head for each crank-guide slidable therealong transversely of the pistons and journaled for rotation on an axis eccentric 10 to the axis of rotation of the shell, driving means for rotating the shell and shaft, a passage from the tank arranged to communicate with the pump cylinders during the suction stroke of the pistons therein, and 15 an outlet passage arranged to communicate with the pump cylinders during the discharge stroke of the pistons therein.

6. In rotary piston pumps, a rotatable shell carrying a plurality of pump cylin-

ders, a rotatable shaft rotatable on an axis 20 eccentric relatively to the axis of rotation of said shell and carrying a plurality of pistons reciprocative in respective cylinders, and driving means engaged with said shaft to drive it and comprising a crank-guide at 25 each end of said shaft, and a rotating guide head for each crank-guide slidable therealong transversely of the pistons and journaled on an axis eccentric to the axis of rotation of the shell.

In testimony that I claim the foregoing as my invention, I have signed my name in presence of two subscribing witnesses.

SVERRE THUNE.
